RULE DEVICE

Arthur Udell, Sayville, N. Y.

Application July 1, 1936, Serial No. 88,269

2 Claims. (Cl. 33—138)

This invention relates to new and useful improvements in a rule device.

The invention has for an object the construction of a rule device which is characterized by an oblong casing having a slot in one end for an extending steel tape and housing a pair of opposed hollowed out blocks longitudinally slidably mounted therein adapted to guide the winding of a steel tape when forced inwards through said slot.

Still further the invention proposes to resiliently mount said hollowed out blocks so that the tape is assisted in assuming the wound position.

A further object of the invention resides in the association of a level and a plumb with the casing.

Still further the invention proposes the association of a stiff rule with the casing which may be extended at right angles thereto and form a square, or may be angularly extended to form a bevel.

A further object of the invention resides in the provision of a novel catch for holding the steel tape extended to various positions.

Still further the invention proposes the association of a slot on the outer extremity of the steel tape into which a pencil may be engaged to facilitate the use of the rule device.

Another object of the invention is the construction of an article as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a rule device constructed according to this invention.

Fig. 2 is a horizontal sectional view taken on the line 2—2 of Fig. 1.

Fig. 2a is a fragmentary enlarged detailed view of a portion of Fig. 2 specifically showing the end of the tape shown in this figure.

Fig. 3 is a fragmentary enlarged sectional view taken on the line 3—3 of Fig. 1.

Fig. 4 is a fragmentary elevational view of a portion of the steel tape.

The rule device, according to this invention, comprises an oblong casing 10 having a slot 11 in one end through which a steel tape 12 may be extended. A pair of opposed hollowed out blocks 13 and 14 are longitudinally slidably

mounted in the casing and are adapted to guide the winding of the steel tape 12 as hereinafter further described.

The steel tape 12 is constructed of flexible material and is guided against one side of the casing 10 by the proper location of the slot 11 aligned therewith. Thus the steel tape is in intimate contact with this side and passes the adjacent side of the block 13. The hollowed out block 14 has its hollow portion aligned to receive the steel tape as it is forced inwards along the side of the casing. This side of the casing is indicated by reference numeral 10a. The tape is then forced around the hollow of the block 14 and follows the contour of the other side of the casing, indicated by reference numeral 10b. From there it is forced to follow the contour of the hollow of the block 13, and in this manner it is wound up.

The inner end of the tape 12 is provided with a block 14' which prevents its complete removal through the slot 11. The outer end of the tape is provided with a stop and gauge element 15 which prevents the outer end from slipping into the casing. This element 15 and the end portion of the tape are provided with aligned elongated slots 16 into which the point of a pencil may be engaged for measuring off distances. The element 15 is of angle form hingedly mounted at one end 15a so it may fold back.

In order that the steel tape does not become jammed between the blocks 13 and 14, these blocks are resiliently mounted. The block 14 is urged towards the block 13 by a spring 18 interposed between the end of the casing and the end of the block. The block 13 is urged towards the block 14 by a spring 19 interposed between the block 13 and indirectly with the other end of the casing.

A means is provided for latching the tape 12 in any extended position. This means comprises a pivotally mounted member 20 having an end 20a adapted to wedge against the tape 12. The member 20 has side lugs 21 engaged by a pin 22 engaging the side walls of a depressed portion 10c in the end of the casing. Thus the member 20 is pivotally mounted. The other end of the member 20 is provided with a button head 20c which may be manually depressed to pivot the member to inoperative position. This button 20c connects with a stem 23 extending into the casing 10 and connected with a support 24 which supports the spring 19. It is the spring 19 which pivots the member 20 and urges it into operative locking position. The block 13 is formed with several slots 25 engaged by pins 26 projecting

from the casing 10 and serving to limit the possible motion thereof.

The casing 10 has one of its walls, the wall 10d, constructed especially thick. This thick wall is formed with a recess 28 communicating with one side. A stiff rule 29 is disposed within this recess. This stiff rule is pivotally mounted at one end by a rivet 30. It is adapted to be extended to various angular positions and to the right angle position indicated by the dot and dash lines in Fig. 1. In this latter position it may be used as a square.

A level 31 is mounted upon the top face of the casing 10 at the center. A plumb 32 is mounted also on the top face of the casing 10 but transverse to the level 31. This level and plumb are constructed according to conventional practice and for this reason the details thereof will not be given in this specification.

The casing 10 has one side, namely the side 10d, formed with an inch scale 33. The top face of the casing is also formed with an inch scale 34. Preferably, the casing 10 should be approximately 8" long and the rule 29 6" long. The steel rule 12 preferably should be formed with a double scale 35a and 35b, as clearly shown in Fig. 4. The scale 35a gives the distance from the outer end of the rule to the near side of the casing 10. The scale 35b starts at 8" because the casing 10 is 8" long and therefore at the near side of the casing 10 gives the distance from the end of the rule to the remote end of the casing 10. The corners of the casing 10 are formed with angle openings 38a and 38b through which the nails 40 may be passed. These nails may secure the device to some article to be leveled or plumbed.

The operation of the device is as follows:—

The head 20c of the lever 20 may be depressed to free the rule 12 which then may be pulled out to any desired amount. While the member 20 is inoperative the rule 12 may be forced inwards and automatically wound as indicated in Fig. 2 of the drawing. The rule will follow the sides of the casing and the hollowed opposed ends of the

blocks 13 and 14. It cannot become stuck or jammed due to the resilient mounting of the blocks.

The rule device may be used wherever measuring and similar operations are necessary.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

1. An extensible rule, including an oblong casing having a slot in one end, a pair of spaced blocks mounted in said casing for sliding movement towards and from each other, said blocks having facing semi-cylindrical hollowed-out portions, a coilable tape extending through said slot into said casing, said hollowed out portions acting to guide the tape into a coil as it is pushed into the casing, and means for resiliently urging at least one block toward the other.

2. An extensible rule, including an oblong casing having a slot in one end, a pair of spaced blocks mounted in said casing for sliding movement toward and from each other, said blocks having facing semi-cylindrical hollowed out portions, a coilable tape extending through said slot into said casing said hollowed out portions acting to guide the tape into a coil as it is pushed into the casing, a spring for resiliently urging one of said blocks toward the other, means for latching said tape in any extended position and including a pivotally mounted operator member, and a stem connecting said operator member with said spring so that the spring urges said latching means into operative locking position.

ARTHUR UDELL.
